UNITED STATES PATENT OFFICE.

KARL VÖLLER, OF DUSSELDORF, GERMANY.

GUN ADAPTED PREFERABLY FOR USE IN SUBMARINE BOATS.

1,095,049.

Specification of Letters Patent. Patented Apr. 28, 1914.

Application filed October 3, 1913. Serial No. 793,121.

To all whom it may concern:

Be it known that I, KARL VÖLLER, engineer, a subject of the German Emperor, residing at 12 Scharnhorststrasse, Dusseldorf, Germany, have invented certain new and useful Improvements in Guns Adapted Preferably for Use in Submarine Boats; and I do hereby declare the following to be a full, clear, and exact description of the invention, such as will enable others skilled in the art to which it appertains to make and use the same.

In an application for patent filed by me June 24, 1913, Serial No. 775,504, I showed and described a disappearing gun especially adapted for use in connection with submarine boats, such gun being capable of being raised from and lowered into a casing the cover of which is raised and lowered currently with the gun. According to the particular form of the invention claimed in said application, the cover of the casing was capable of recoiling with the gun barrel, and in consequence the recoiling mass was considerably increased, thereby enabling the use of a comparatively large bore. In the present instance the cover of the casing is not designed to recoil with the barrel, but on the other hand is utilized to form a counterweight, that is to say, the cover is capable of being moved relatively to the gun barrel to counterbalance the forward end thereof. In elevating the gun the center of gravity is rocked around the axis of the trunnions, and I make the cover adjustable in such a manner that it can be shifted to maintain the equilibrium of the system. Such shifting of the cover can be performed by hand, and for that purpose index marks may be provided to indicate the required length of the adjustment in every case. But my invention also comprises means for shifting the cover automatically as the barrel is elevated as by means of a cam. By means of locking mechanism the cover can be fixed in the desired position.

In cases in which the position of the trunnions is so chosen that their axis passes through the center of gravity of the rocking system, the weight of the forward part of the gun may be counterbalanced once and for all by the cover without providing means for shifting the latter.

If it is preferred to utilize the cover as a

shield against projectiles it may be protected with steel armor.

In the accompanying drawings, Figure 1 is a sectional elevation illustrating an embodiment of the invention, the gun being shown in its lowered position; and Fig. 2 is a sectional elevation showing the gun in an elevated position. Fig. 3 shows a slight modification.

Referring to the drawings, *a* designates the deck of a submarine boat; *b*, uprights for supporting a casing or chamber *c*, capable of receiving and inclosing the gun, said casing depending from the deck. The gun barrel *d* is capable of recoiling, according to known means, in a cradle *h* which is supported on the upper end of a vertically movable plunger *f* by means of trunnions *e*, said plunger being fitted in a cylinder *g* and adapted to be operated by water pressure so that by reciprocating the plunger the gun may be raised into and lowered out of firing position. Any suitable means may, however, be employed for effecting the raising and lowering of the gun. The plunger *f* may also serve as a pivot to swing the gun horizontally.

The cover *c* for casing *a* instead of being attached directly to the gun barrel after the manner disclosed in my before noted application for patent, is connected to cradle *h* by means of links *i*. Rigidly affixed to the cradle are locking means *k* by which the cover may be locked in different positions relatively to the barrel.

When the gun is lowered, as shown in Fig. 1, the cover is so located with relation to the gun that its weight does not counterbalance the forward part of the gun barrel, but by swinging the cover backward, when it and the gun are raised, and locking it in the desired position by means of the locking means *k*, such cover may be brought into a position in which it exactly counterbalances the weight of the forward end of the gun in any desired elevation. The couple produced by the action of gravity upon the forward end of the gun varies inversely with the elevation, and by thus providing means for variously adjusting the cover these variations of the couple can be equalized.

In the form shown in Fig. 3 the cover is automatically shifted by a slotted cam member *l* of the gun bearing and a removable pin

m mounted on the rear link *i*. The cam slot is so shaped that in elevating the gun the cover is shifted in accordance with the variations of the center of gravity, thus balancing the weight in all instances.

5 I claim as my invention:

1. In combination with a gun adapted for use in submarine boats, a casing for said gun, a cover for said casing, means connecting said cover to the gun, the weight of said cover when the gun is in firing position serving to counterbalance the forward end of the gun barrel, and means for raising and lowering the gun and cover.
- 10 2. In combination with a gun adapted for use in submarine boats, a casing for said gun, a cover for said casing, means adjustably connecting said cover to the gun, the weight of said cover when the gun is in firing position serving to counterbalance the forward end of the gun barrel, and means for raising and lowering the gun and cover.
- 15 3. In combination with a gun adapted for use in submarine boats, a casing for said gun, a cover for said casing, means adjustably connecting said cover to the gun, the weight of said cover when the gun is in firing position serving to counterbalance the forward end of the gun barrel, and means for raising and lowering the gun and cover.
- 20 4. In combination with a gun adapted for use in submarine boats, a casing for said gun, a cover for said casing, means adjustably connecting said cover to a non-recoiling part of the gun, locking means for the last mentioned means, and means for raising and lowering the gun and cover.

3. In combination with a gun adapted for use in submarine boats, a casing for said gun, a cover for said casing, said cover being connected to a non-recoiling part of the gun, and movable relatively to the gun barrel to counterbalance the forward end thereof, and means for raising and lowering the gun and cover.

4. In combination with a gun adapted for use in submarine boats, a casing for said gun, a cover for said casing, means adjustably connecting said cover to a non-recoiling part of the gun, locking means for the last mentioned means, and means for raising and lowering the gun and cover.

In testimony whereof, I have signed this specification in the presence of two subscribing witnesses.

KARL VÖLLER.
